(57) **CLAIM**

The ornamental design for a disc jockey performance controller, as shown and described.

DESCRIPTION

FIG. 1 is a perspective view of a disc jockey performance controller showing our new design;

FIG. 2 is a top view thereof;

FIG. 3 is a bottom view thereof;

FIG. 4 is a front elevational view thereof;

FIG. 5 is a rear elevational view thereof;

FIG. 6 is a left side elevational view thereof; and,

FIG. 7 is a right side elevational view thereof.

The switches, sliders, indicators, knobs, buttons, logo, vent holes and fasteners are shown in broken lines on FIGS. 1-7 are for illustrative purposes only and form no part of the present invention.

1 Claim, 7 Drawing Sheets

FIG. 2

FIG. 3

FIG. 4

FIG. 5

FIG. 6

FIG. 7
